BALANCING DEVICE

Wilfrid E. Johnson, Schenectady, N. Y., assignor
to General Electric Company, a corporation
of New York

Application October 24, 1935, Serial No. 46,568

6 Claims. (Cl. 74—604)

My invention relates to balancing devices and more particularly to balancing devices especially adapted for use in connection with refrigerant compressors, or the like.

5 Refrigerating machines ordinarily include a refrigerant compressor in which vaporized refrigerant is compressed in one or more cylinders by suitable reciprocating pistons, the latter usually being driven by an electric motor. During 10 the reciprocation of the compressor pistons in their respective cylinder bores, they are rapidly accelerated in one direction, then decelerated as they approach the end of their travel in that direction, then rapidly accelerated in the opposite 15 direction and again decelerated as they approach the end of their travel in this opposite direction. By the term "pistons" I, of course, intend to include not only the pistons themselves, but the other parts attached thereto which 20 also have a reciprocatory movement. This rapid acceleration and deceleration of the pistons in opposite directions is opposed by the inertia of the pistons, which tends to cause them to maintain a motion of constant velocity in any particular 25 direction in which they may move. That is, an inertia force is set up by the pistons, which varies directly as the rate of change of velocity of movement of the pistons and, which reacts on the driving shaft of the driving motor and, 30 consequently, on other apparatus attached thereto. This inertia force is thus of a reciprocatory or vibratory character and results in an undesirable vibration of the driving motor and compressor. Such a vibration of the parts of the 35 refrigerating machine which, of course, increases the noise of its operation is particularly undesirable in the case of machines, designed for household use, for cooling either a room or a food storage compartment of a refrigerator cabinet.

40 Since a refrigerant compressor of the reciprocating type ordinarily operates at a substantially constant normal running speed, the frequency of the forces applied thereto, due to the inertia of the reciprocating parts, is also substantially constant. It has been, heretofore, proposed in 45 balancing masses, subjected to a vibratory force of constant frequency, to attach thereto a second mass by means of a spring or other resilient connection having such characteristics that the 50 second mass has a natural frequency of vibration equal to the frequency of the disturbing force. In such case, the vibrations of the second mass are substantially 180° out of phase with respect to the disturbing force applied to the 55 first mass and the inertia force of the second

mass, which is thus exactly opposite in time phase, cancels the applied force. The net result is that the first mass remains substantially stationary. Such an arrangement is ordinarily termed a "dynamic balancer". It is obviously not feasible to use a dynamic balancer of this type on a compressor piston, for example, since the piston must have a reciprocatory motion in order to perform its primary compressing function in the machine.

It is an object of my invention to provide an improved balancing arrangement for the reciprocating parts of a refrigerant compressor, or the like, in which the reciprocating parts of the compressor move with a substantially constant periodicity and amplitude of movement and in which the inertia forces, resulting from such movement, are exactly balanced. I accomplish this by providing a balance weight, or similar mass, which cooperates with the moving parts to be balanced through a suitable resilient connection. The resilient connection is so arranged that the entire system, composed of the reciprocating parts of the compressor, the balance weight, and the resilient connection, has a combined natural frequency of vibration substantially equal to the frequency of the inertia forces set up by the reciprocating parts of the compressor, as contrasted with the ordinary dynamic balancer in which the balance weight and resilient connection alone have a natural frequency of vibration equal to the frequency of the disturbing forces applied to the mass which is to be balanced.

I have found, however, that difficulty is encountered in the operation of a balancing device of the general preferred type, described above, during the periods in which the inertia forces to be balanced are of a lower frequency than the natural frequency of the system heretofore defined as, for example, during the starting period of the machine. Thus, during the starting period of the machine, the frequency of the inertia forces set up by the reciprocating parts of the machine gradually increases from a value of zero, when the machine is at rest, to a normal maximum value at full running speed. At some point between these two values of frequency, the inertia forces attain a frequency which is just equal to the natural frequency of the balance weight and its resilient connection alone. Consequently, a condition of resonance is had in which the balance weight tends to have an infinite amplitude of vibration which, in practice, is limited only by friction and the ob-

55

struction afforded to the movement of the balance weight by its mounting. At a result, the balance weight vibrates with such great force at this resonance speed that a severe pounding 5 in the machine ensues. If a coil spring, for example, is used as the resilient connection for the balance weight, it will be completely collapsed by the balance weight and a heavy blow is delivered to the machine when the spring thus 10 collapses or "goes solid." If this condition persisted only at a speed of the machine at which this resonant condition first occurred and then stopped as soon as a higher speed was reached, it might be possible to accelerate the machine 15 with sufficient rapidity that the resonant point could be passed without inflicting serious injury on the machine. I have found that this is not the case, however, but that on the other hand when such a pounding of the balance weight once 20 starts during a period of resonance that it continues at all higher speeds, so that a proper operation of the balancing device is never had. This apparently results from the fact that the shock of the impact on the balance weight when 25 its connecting spring collapses imparts an added restoring force thereto tending to move the balance weight in the opposite direction at an even higher speed than the compressed spring itself would normally accomplish. Consequently, the 30 effective natural frequency of the balance weight and its resilient connection is progressively increased in direct proportion to the increase in speed of the machine and a condition of pseudo-resonance results in which the pounding of the 35 balance weight continues with steadily increasing force at all higher speeds.

It is a further object of my invention to provide a balancing device of the type described for a refrigerant compressor, or the like, in which the 40 reciprocating parts of the machine, a balance weight, and a resilient connection therebetween form a dynamic system having a combined natural frequency substantially equal to the frequency of the inertia forces set up by the moving 45 parts of the compressor at the normal running speed of the compressor and an arrangement for preventing a pseudo-resonance condition in the machine, due to the action of the balanced weight, when the machine is operating at 50 other than its normal running speed. I accomplish this by providing an arrangement for varying the rate of change in the force applied to the balance weight by the resilient connection therefor when the amplitude of movement of 55 the balance weight reaches a predetermined maximum. By so varying the rate of change in the force applied to the balance weight its natural frequency of vibration on the resilient connection is varied and, consequently, the resonant or 60 pseudo-resonant condition is avoided.

Further objects and advantages of my invention will become apparent as the following description proceeds and the features of novelty which characterize my invention will be pointed 65 out with particularity in the claims annexed to and forming a part of this specification.

For a better understanding of my invention reference may be had to the accompanying drawing, in which Fig. 1 is a side elevation, partly in 70 section, of a refrigerant compressor provided with a balancing device embodying my invention; Fig. 2 is an enlarged sectional bottom plan view along the line 2—2 in Fig. 1 of the balancing device and a portion of the compressor shown in 75 Fig. 1; and Fig. 3 is a graph illustrating the re-

lation of the amplitude of movement of the compressor reciprocating parts and of the balance weight therefor with respect to variations in speed of the compressor drive shaft, for the machine illustrated in Figs. 1 and 2.

5

Referring to the drawing, I have shown in Fig. 1 a refrigerant compressor 10 of the Scotch yoke type designed for household use and which is driven by an electric driving motor 11 having a vertical driving shaft 12. The compressor 10 includes a cylinder 13 having a horizontal cylindrical bore 14. A horizontal cylindrical reciprocatable member or piston 15 is reciprocated in the cylinder bore 16 by the driving motor 11. In the illustrative form of my invention, the driving motor 11 is connected to the compressor piston 15 through a Scotch yoke mechanism which includes a cylindrical cross yoke 16 which is rigidly secured to the outer end of the piston 15 at right angles thereto. A cylindrical slide block 17 is slidably mounted in the yoke 16 and has a vertical cylindrical hole 18 formed therein which receives an eccentric crank pin 19. It will be noted that the crank pin 19 extends through an elongated slot 16a formed in the bottom of the yoke 16. A rotating counterweight 20 is rigidly secured to the top of the motor driving shaft 12 and the crank pin 19 is rigidly secured to the top of the counterweight 20 eccentrically with respect to the motor driving shaft 12. Upon rotation of the motor driving shaft 12, the compressor piston 15 is reciprocated in the cylindrical bore 14, the slide block 17 having a reciprocating motion in the yoke 16.

30

In the operation of the refrigerant compressor, described above, the rotating forces or couples which would otherwise tend to cause a vibration of the machine are balanced by a suitable set of rotating counterweights, one of which is indicated at 20. Due to the inertia of the reciprocating piston 15, reciprocatory forces are applied to the compressor tending to cause vibration of the same during its normal operation. Since the compressor 10 normally operates at a constant running speed, the frequency of the reciprocatory disturbing forces applied thereto is also substantially constant during such normal operation.

40

I have provided a balancing device embodying my invention for the refrigerant compressor 10 in which a reciprocatable balance weight 21 is utilized to balance or counteract the reciprocatory or vibratory inertia forces exerted on the compressor by the piston mechanism. The balance weight 21 is cylindrical and is provided with laterally extending cylindrical projections 22 and 23 on the opposite sides thereof. A cylindrical bore 24 extends axially through the counterweight 21 and the projections 22 and 23, the longitudinal axis of the bore 24 being substantially coincident with an axis of symmetry of the counterweight 21 and its projections 22 and 23. The counterweight 21 is slidably mounted on the cylindrical guide rod 25 which is positioned in the bore 24 formed therein. The inner end of the guide rod 25 is rigidly secured to the side of the yoke 16 which forms a part of the piston mechanism and the guide rod 25 is arranged substantially in axial alignment with the piston 15. The outer end of the guide rod 25 is slidably supported in a bore 26 formed in the upper end of an L-shaped bracket 27, the lower end of which is secured to the top of the driving motor 11 by a bolt 28.

50

The balance weight 21 is biased to a predetermined position with respect to the piston mecha-

55

60

65

70

75

nism by a resilient arrangement exerting a variable biasing force thereon proportional to the amplitude of displacement of the balance weight which preferably includes a pair of helical compression springs 29 and 30 positioned on opposite sides of the balance weight 21 and surrounding the guide rod 25. The inner ends of the springs 29 and 30 surround the lateral projections 22 and 23 of the balance weight 21 and are tightly fitted 5 in suitable helical grooves formed in the surfaces of the lateral projections 22 and 23. The inner ends of the springs 29 and 30 are thus rigidly secured to the balance weight 21. The axial or lateral movement of the springs 29 and 30 is 10 limited by a pair of stops or collars 31 and 32 which are rigidly secured to the guide rod 25 by pins 33 and 34, respectively.

The collars 31 and 32 are positioned sufficiently close together on the guide rod 25 that both of the springs 29 and 30 are somewhat compressed even when the balance weight 21 is at rest. The mass of the balance weight 21 is so proportioned with respect to the masses of the reciprocating parts of the compressor which include the piston 15, the 15 yoke 16, the guide rod 25, and the collars 31 and 32 and with respect to the resilient characteristics of the springs 29 and 30 that the entire dynamic system, composed of reciprocating parts of the compressor, the balance weight 21 and the springs 29 and 30 will have a natural frequency of vibration substantially equal to the frequency of the reciprocatory forces resulting from the inertia of the reciprocating parts of the compressor. I have found that, if the outer ends of the springs 29 and 35 30 are fixed with respect to the guide rod 25, that difficulty is experienced in operating the mechanism, described above, especially during the acceleration period of the compressor. During the starting period of the machine, the frequency of 40 the inertia forces set up by the reciprocating parts of the machine gradually increases from a value of zero, when the machine is at rest, to a normal maximum value at full running speed. At some point between these two values of frequency, the 45 inertia forces attain a frequency which is just equal to the natural frequency of the balance weight 21 and its resilient connecting springs 29 and 30. Consequently, if the outer ends of the springs 29 and 30 are fixed with respect to the 50 guide rod 25, a condition of resonance is had in which the balance weight 21 tends to have an infinite amplitude of vibration which is, in practice, limited only by friction and by the obstruction afforded to its movement by the collars 31 and 32. As a result, the balance weight vibrates 55 with such great force at this resonance speed that it pounds heavily against the collars 31 and 32. The helical springs 29 and 30 are completely collapsed by the balance weight 21 and a heavy blow 60 is transmitted therethrough to the collars 31 and 32. I have found that when this pounding of the balance weight once starts during such a period of resonance that it continues at all higher speeds so that a proper operation of the balancing device 65 is not attained.

In order to overcome this difficulty, I have provided a pair of cylindrical spring plugs 35 and 36 which are slidably mounted on the guide rod 25. The outer ends of the helical springs 29 and 30 are 70 tightly fitted in suitable helical grooves formed in the surfaces of the spring plugs 35 and 36 and are thus rigidly secured thereto. It will thus be seen that the outer ends of the springs 29 and 30 are free to move with respect to the guide rod 25 after 75 the balance weight 21 passes through a predeter-

mined amplitude of reciprocation. Washers 37 and 38, made of fiber, felt, or other sound-deadening material, are preferably positioned on the inner faces of the collars 31 and 32, in order to minimize any noise which might otherwise result 5 from the striking of the spring plugs 35 and 36 against the collars 31 and 32, respectively.

Since the spring plugs 35 and 36 are movable with respect to the guide rod 25 when the balance weight 21 attains a predetermined amplitude of 10 reciprocation, the "spring constant" or rate of change in the force applied to the balance weight 21 by the springs 29 and 30 is also changed when this predetermined amplitude of movement of the balance weight 21 is attained. By so decreasing 15 the rate of change in the force applied to the balance weight 21, its natural frequency of vibration on the springs 29 and 30 is varied and, consequently, the resonant or pseudo-resonant condition is avoided and it is possible to accelerate the 20 compressor on up to its normal running speed without having the balance weight 21 pound the collars 31 and 32 due to such a pseudo-resonant condition.

In the operation of the machine, described 25 above, when the driving motor 11 is started the driving shaft 12 is rotated at a gradually increasing speed and, similarly, the compressor piston 15 is reciprocated at a gradually increasing speed 30 although with a constant amplitude of movement. When the piston 15 and guide rod 25 are first slowly reciprocated, the balance weight 21 moves back and forth substantially in phase therewith since there is sufficient friction between the balance weight 21 and the guide rod 25 to cause the 35 balance weight to reciprocate with the rod. As the speed of the compressor piston 15 is increased, however, the balance weight 21 gradually begins to reciprocate with a steadily increasing amplitude due to its inertia. The springs 29 and 30 40 exert a restoring force on the balance weight 21 tending to move it back to its predetermined position with respect to the guide rod 25 against the action of the forces set up by the inertia of the 45 balance weight 21.

When the speed of the compressor reaches such a value that the frequency of the inertia forces set up by the reciprocating parts of the compressor is substantially equal to the natural 50 frequency of the balance weight 21 and springs 29 and 30, a resonant condition is had in which the balance weight tends to reciprocate substantially 180° out of phase with respect to the piston 15 and with an infinite amplitude of movement. As soon as the balance weight moves 55 far enough to the right, for example, that the spring 29 is no longer compressed the spring plug 35 moves to the right away from the collar 31. At this instant the spring constant or, in other words, the rate of change in the forces 60 applied to the other weight 21 by the springs 29 and 30 is changed. In order for the rate of change in the force applied by the springs 29 and 30 to be constant the outer end of the spring 29 would have to be fixed so that the therefore 65 decreasing compressive force exerted by the spring 29 on the balance weight 21 would become negative, that is, so that the spring 29 would be in tension. Since in the arrangement 70 which I have provided, however, the rate of change in the force applied to the balance weight 21 by the springs 29 and 30 does change, as soon as the balance weight 21 reaches this predetermined amplitude of reciprocation the natural frequency of the balance weight 21 on the 75

springs 29 and 30 is at once lowered and, consequently, the resonant condition no longer prevails since the natural frequency of the balance weight and springs 29 and 30 does not coincide with the frequency of the inertia forces applied thereto by the reciprocating parts of the compressor.

As heretofore pointed out, the masses of the reciprocating parts of the compressor and the mass of the counterweight 21, as well as the resilient characteristics of the springs 29 and 30, are so proportioned that the dynamic system, composed of the reciprocating parts of the compressor, the balance weight 21, and the springs 15 29 and 30, has a natural frequency substantially equal to the frequency of the inertia forces set up by the reciprocating parts of the compressor. Consequently, these inertia forces are exactly balanced by the out of phase inertia forces set 20 up by the balance weight 21 in the dynamic system defined. This action is graphically illustrated in Fig. 3, which represents the amplitude of reciprocation of the piston as well as of the balance weight 21 at various speeds of rotation 25 of the drive shaft 12. The curves shown in Fig. 3 are plotted for a construction in which the inertia of the reciprocating parts of the compressor is substantially equal to the inertia of the balance weight 21. In that case, the inertia 30 forces set up by the reciprocating parts of the compressor will be exactly balanced by the balance weight 21 when the amplitude of reciprocation of the reciprocating parts of the compressor is exactly equal to the amplitude of reciprocation 35 of the balance weight 21 and opposite in phased relation thereto. From an inspection of Fig. 1 it will be seen that the piston mechanism, that is, the reciprocating parts of the compressor has a constant amplitude of reciprocation as is, of 40 course, necessary due to the construction of the machine. It will be seen that as the speed of the machine increases, the amplitude of the reciprocation of the balance weight increases until it tends to become infinite at approximate- 45 ly 15 cycles per second which is substantially the resonant speed of the machine illustrated. At this point the reciprocation of the balance weight 21 becomes 180° out of phase with respect to the inertia forces set up by the piston mech- 50 anism. From that point on, the amplitude of reciprocation of the balance weight 21 gradually decreases until at the normal running speed of the machine which is about 30 cycles per second in the machine illustrated. The amplitude of 55 reciprocation of the piston mechanism and balance weight 21 are both equal to the same value A.

From a consideration of the graphical illustration of the operating characteristics of my 60 improved balancing device shown in Fig. 3, it will be seen that the balancing device is effective in counteracting the inertia forces set up by the piston mechanism at all speeds above the resonant speed of the balance weight 21 on the 65 springs 29 and 30. This fact is of particular importance in that it allows a fairly wide latitude of error in the design, as well as the manufacture of the various parts of the machine. This is true since a condition of approximate balance 70 is had at all speeds close to the normal running speed and even at those varying an appreciable amount therefrom. This characteristic operation of my improved balancing device is very different from that prevailing in an or-

dinary "dynamic balancer" of the type heretofore described. That is, in an ordinary dynamic balancer, the balance weight is effective in maintaining the body to be balanced in a substantially stationary condition only at the critical resonant speed indicated in the graph in Fig. 3. It will be seen that the action of the balance weight varies sharply with a slight change in speed from the critical value and, consequently, a careful design of the parts as well as great care in 10 the manufacture thereof would be required.

While I have shown a particular embodiment of my invention in connection with a refrigerant compressor designed for household use, I do not desire my invention to be limited to the 15 particular construction shown and described and I intend, in the appended claims, to cover all modifications within the spirit and scope of my invention.

What I claim as new and desire to secure by 20 Letters Patent of the United States, is:

1. In combination, a compressor or the like including a reciprocatable member exerting a vibratory force thereon of substantially constant frequency when said compressor is operating at its normal running speed, a balancing device therefor comprising a reciprocatable balance weight, means for resiliently connecting said balance weight and said reciprocatable member and for mounting said balance weight on said reciprocatable member and movably with respect thereto, the inertias of said reciprocatable member and said balance weight being proportioned with respect to the elastic characteristics of said resilient means to form a dynamic system composed of said reciprocatable member and said balance weight and resilient means having a combined natural frequency of reciprocatory oscillation substantially equal to said constant frequency of said vibratory force, and means for reducing the force applied to said balance weight by said resilient connection when the amplitude of reciprocation of said balance weight reaches a predetermined maximum.

2. In combination, a compressor or the like including a reciprocatable member exerting a vibratory force thereon of substantially constant frequency when said compressor is operating at its normal running speed, a balancing device therefor comprising a reciprocatable balance weight, means resiliently exerting a variable biasing force on said balance weight proportional to the amplitude of reciprocation thereof for biasing said balance weight to a pre-determined position with respect to said reciprocatable member and for mounting said balance weight on said reciprocatable member and movably with respect thereto, said reciprocatable member and said balance weight and said resilient means having a combined natural frequency of reciprocatory oscillation substantially equal to said constant frequency of said vibratory force, and means for reducing the rate of variation of said biasing force exerted on said balance weight by 65 said resilient means during the acceleration period of said compressor when the amplitude of reciprocation of said balance weight reaches a predetermined maximum to prevent a pseudo-resonance condition in the system composed of said reciprocatable member and balance weight and resilient means during such acceleration period.

3. In combination, a compressor or the like in-

cluding a reciprocatable member exerting a vibratory force thereon of substantially constant frequency when said compressor is operating at its normal running speed, a balancing device therefor comprising a reciprocatable balance weight, means including compression springs positioned on opposite sides of said balance weight and exerting a variable force on said balance weight proportional to the amplitude of reciprocation thereof for biasing said balance weight to a predetermined position with respect to said reciprocatable member and for mounting said balance weight on said reciprocatable member and movably with respect thereto, said reciprocatable member and balance weight and resilient means having a combined natural frequency of reciprocatory oscillation substantially equal to said constant frequency of said vibratory force, and means for reducing the rate of variation 20 of said biasing force exerted on said balance weight by said resilient means during the acceleration period of said compressor when the amplitude of reciprocation of said balance weight reaches a predetermined maximum to prevent a pseudo-resonance condition in the system composed of said reciprocatable member and balance weight and resilient means during such acceleration period.

4. In combination, a compressor or the like including a reciprocatable member exerting a vibratory force thereon of substantially constant frequency when said compressor is operating at its normal running speed, a balancing device therefor comprising a reciprocatable balance weight, means including a guide rigidly secured to said reciprocatable member for slidably supporting said balance weight, resilient means including compression springs positioned on opposite sides of said balance weight and exerting a variable biasing force on said balance weight proportional to the amplitude of reciprocation thereof for biasing said balance weight to a predetermined position with respect to said reciprocatable member, said reciprocatable member and balance weight and resilient means having a combined natural frequency of reciprocatory oscillation substantially equal to said constant frequency of said vibratory force, and means for reducing the rate of variation of said biasing force exerted on said balance weight by said resilient means during the acceleration period of said compressor when the amplitude of reciprocation of said balance weight reaches a predetermined maximum to prevent a pseudo-resonance condition in the system composed of said reciprocatable member and balance weight

and resilient means during such acceleration period.

5. In combination, a compressor or the like including a reciprocatable piston exerting a vibratory force thereon of substantially constant frequency when said compressor is operating at its normal running speed, a balancing device therefor comprising a reciprocatable balance weight, means including a guide rod rigidly secured to said piston in axial alignment therewith for slidably supporting said balance weight, resilient means including compression springs rigidly secured to opposite sides of said balance weight and surrounding said guide rod for biasing said balance weight to a predetermined position with respect to said piston, said piston and balance weight and resilient means having a combined natural frequency of reciprocatory oscillation substantially equal to said constant frequency of said vibratory force, spring plugs slidably mounted on said guide rod and secured to the outer ends of said compression springs, and means including stops for limiting the axial movement of said spring plugs, said stops being positioned to slightly compress said springs when said compressor is at rest.

6. In combination, a compressor or the like including a reciprocatable piston exerting a vibratory force thereon of substantially constant frequency when said compressor is operating at its normal running speed, a balancing device therefor comprising a balance weight having laterally extending projections formed thereon and having a bore extending therethrough and through said lateral projections, means including a guide rod positioned in said bore and rigidly secured to said piston in axial alignment therewith for slidably supporting said balance weight, resilient means including helical compression springs surrounding said guide rod and having their inner ends secured to said lateral projections on said balance weight for biasing said balance weight to a predetermined position with respect to said piston, said piston and balance weight and resilient means having a combined natural frequency of reciprocatory oscillation substantially equal to said constant frequency of said vibratory force, means for slidably supporting the outer ends of said springs on said guide rod, means including stops positioned on said guide rod for limiting the axial movement of said compression springs and balance weight, and means for minimizing the noise resulting from the striking of said springs against said stops.

WILFRID E. JOHNSON.
